DRY SHAVING IMPLEMENT

Joseph Muros, Cambridge, Mass., assignor to
Gillette Safety Razor Company, Boston, Mass.,
a corporation of Delaware

Application December 9, 1938, Serial No. 244,825

2 Claims. (Cl. 30—43)

This invention relates to shaving implements of the type employing a head or holder which is removable intact from the body of the implement and which contains a movable cutter member that is readily disengaged from the head.

The object of the present invention is to retain the cutter yieldingly within the head and prevent accidental displacement and loss when the head is removed from the handle of the implement for cleaning or for any other purpose. When the head is assembled in the implement in its operative position the position of the movable cutter is controlled by a connection with its operating mechanism and this mechanism also prevents the accidental release and loss of the cutter. However, when the head is removed from the handle of the implement, as it often is for purposes of cleaning, the operating mechanism is disengaged from the cutter and in implements as heretofore constructed the cutter is then free to slide out of the head and fall upon the floor or down the drain of the sink to the great annoyance of the user. This condition is aggravated by the fact that the cutter is usually a thin, flat bar of small dimensions and is hard to find when once dropped or misplaced. Various mechanical expedients have been tried for retaining or limiting the movement of the cutter bar but these have not proved satisfactory because of the small space available or because they impose an added load to the motor of the implement.

The present invention consists in a dry shaving implement having one or more of its steel head parts permanently magnetized in such manner that the cutter is magnetically retained in the head independently of its operating mechanism and in whatever position the head may be placed. It is contemplated that the external part of the head in which the stationary shearing teeth are formed or the cutter bar or both of these parts may be magnetized according to the design of the shaving implement. In those implements wherein the outer member of the head is substantially U-shaped it is desirable to magnetize this part since the cutter bar interposed between its two side portions acts as a keeper completing the magnetic circuit and thus maintains the stationary member permanently and fully magnetized. In this or in other constructions it may be sufficient to magnetize the cutter bar only.

In all instances it will be noted, however, that on account of its small amplitude, the movement of the cutter bar takes place entirely within the magnetic field of the head so that no additional

duty is imposed on the motor. On the other hand, when the cutter bar is moved substantially out of mid position further movement is increasingly resisted and the weight of the cutter bar is insufficient to disengage it even though the head may be held with its major axis vertical. The possibility of accidental displacement and loss of the cutter bar is thus obviated although the cutter bar may still be forceably removed at any time desired by the user.

It is within the scope of the invention to magnetize both the outer parts and the cutter parts of the implement and under these conditions a very desirable condition may be realized, that is to say, the correct relation, end-for-end, of the cutter and the head may be insured, for if the attempt is made to insert the cutter wrong end first the polarity of the cutter is such as to cause it at once to be ejected by the repulsion of like poles. The user is thus warned that he must reverse the cutter bar and insert it under conditions which tend to draw it into the head rather than to expel it.

These and other features of the invention will be best understood and appreciated from the following description of a preferred embodiment thereof, selected for purposes of illustration and shown in the accompanying drawing, in which:

Fig. 1 is a view in side elevation, with parts broken away, showing a dry shaving implement with the head in assembled operative position;

Fig. 2 is a view in longitudinal section showing the head in assembled position, and

Fig. 3 is a similar view showing the head disengaged from its socket.

The invention is herein shown as embodied for illustrative purposes in an implement of the type disclosed in the co-pending application of Muros & Lewando, Serial No. 154,376, filed July 19, 1937. Only so much of the implement is illustrated as is required for a complete understanding of the invention. It includes in its structure a handle 10 of "Bakelite" or similar material which serves also as a casing for the motor of the implement. The end of the operating lever 11 oscillated by the motor is shown in Figs. 2 and 3 but the motor itself is not shown in the drawing since it forms no part of the invention.

The casing is provided at its ends with transverse parallel flanges or ribs 12 forming a socket for the metallic head of the implement. The head comprises a pair of steel side members 13 each provided with an inwardly overhanging flange 14 slotted to provide stationary shearing teeth. The side members 13 are rigidly secured together by

bolts 16 passing through spacing blocks 15. The blocks 15 together with the side walls of the members 13 and their flanges 14 form an elongated passage in which the cutter bar 17 is arranged for reciprocation. The cutter is flanged in its outer side and slotted to supply shearing teeth 18 which co-operate with the stationary teeth of the head. The inner face of the cutter 17 is provided with a central notch to receive the outer end of the operating lever 11 and is further provided with two intermediate notches or depressions to receive the ends of spring plungers 19 which project yieldingly from casings 20 located in corresponding sockets in the handle 10. It will be understood that the function of the spring plungers 19 is to hold the cutter 17 pressed yieldingly outward so that its teeth 18 make shearing engagement with the stationary teeth of the head.

The spring plunger 19 and its casing 20 are assembled in a novel manner particularly adapting them for use in dry shaving implements. Each plunger is provided with an enlarged flat circular head located within the flanged outer end of the casing and from the inner face of the head projects a short guide stud by which a coiled compression spring is centered within the casing. The flanged end of the casing furnishes an opening of greater diameter than the plunger 19 so that the latter may rock freely as the cutter reciprocates while the flattened head of the plunger is always pressed yieldingly outward so that no opening ever occurs into which the shaving debris might find its way into the casing 20.

In Figs. 1 and 2 the head is shown as secured in operative position within its socket in the handle. In this position the cutter 17 is engaged both by the operating lever 11 and the spring plungers 19, so that it is positively prevented from passing endwise out of the passage in which it reciprocates in the head. It is necessary or convenient, however, frequently to release the head and remove the cutter 17. The head 13 and the cutter 17 enclosed therein form a complete self-contained unit and when the head is released it may be removed from the handle in intact condition with the cutter therein. When the head is released from its socket and moved outwardly with respect to the handle as shown in Fig. 3 both the operating lever 11 and the spring plungers 19 are disengaged from their respective notches in the cutter 17, and unless otherwise prevented, particularly with the implement positioned as shown in Fig. 3, the cutter is free to slip out of its passage and become lost. This is prevented as herein shown by permanently magnetizing the head, that is to say, the steel side members 13 and the intermediate blocks 15. A powerful permanent magnet of approximately U-shaped cross-section is thus provided and between the sides of this is mounted the rectangular steel cutter bar 17 which thus acts as a keeper to complete the path of the magnet circuit.

When the cutter 17 is in its operative position it is entirely enclosed by the head and its oper-

ating amplitude of movement is so small that it is not carried out of the magnetic field of the head. Consequently, the magnetism of the head has little or no retarding effect upon the normal shearing stroke of the cutter. If the cutter should be displaced to any substantial amount the magnetic force of the head tends strongly to arrest further movement and this is sufficient to overcome the weight of the cutter and prevent it from dropping out of the head. In Fig. 3 the cutter is shown as displaced to the point at which its falling movement is magnetically arrested. Thus accidental displacement of the cutter is obviated although the user may at any time forcibly overcome the magnetic attraction between the two members and so remove the cutter.

While I prefer to magnetize the head, useful results may be secured by magnetizing the cutter alone or by magnetizing both the head and the cutter. In the latter case an additional advantage may be secured by imparting magnetism of opposite polarity to the two members when assembled in the proper relation. Under these conditions the cutter tends always to assume its normal mid-position when inserted with the proper end first while, if the attempt is made to insert the wrong end of the cutter, the like polarity of the parts tends to eject the cutter and so warn the user that the parts are improperly assembled. This is important because the cutter is lapped into the head in a predetermined position and is likely not to fit so well or shave so efficiently if reversed.

I have found it good practice to reverse the cutter temporarily in the head, then magnetize both parts together upon a magnetic chuck so that they have the same polarity and subsequently assemble the parts with opposite polarity and with the cutter in its lapped position.

Having thus disclosed my invention I claim as new and desire to secure by Letters Patent:

1. A dry shaving implement having a removable steel head which is magnetized and substantially U-shaped in cross section, and a reciprocating steel cutter contained within the head forming therewith a removable self-contained unit and serving as a keeper between the sides of the magnetized head the cutter being removable from the head by endwise movement.

2. A dry shaving implement having a handle, a self-contained unit comprising a shearing head member enclosing a reciprocating cutter member, mechanism within the handle operatively connected to said cutter member and positively limiting its movement within the head member, clamping means for holding the head member in place in the handle, said means being releasable to disengage the head member for removal in intact condition as a unit with the enclosed cutter member therein, one of said members being magnetized to retain the cutter member when the said unit is so removed from the handle.

JOSEPH MUROS.
